UNITED STATES PATENT OFFICE

150,797

DESIGN FOR A PIPETTE SUPPORT

David Lane, Philadelphia, Pa.

Application July 10, 1946, Serial No. 131,458

Term of patent 14 years

(Cl. D80—9)

To all whom it may concern:

Be it known that I, David Lane, a citizen of the United States, residing at Philadelphia, in the county of Philadelphia and Commonwealth of Pennsylvania, have invented a new, original, and ornamental Design for Pipette Supports, of which the following is a specification, reference being had to the accompanying drawings, forming part thereof.

Fig. 1 is a front perspective view of a pipette support, showing my new design;

Fig. 2 is a top plan view;

Fig. 3 is a front elevational view; and

Fig. 4 is a side elevational view thereof.

I claim:

The ornamental design for a pipette support, substantially as shown.

DAVID LANE.
